United States Patent Office.

SAMUEL J. PARKER, OF WILLIAMSPORT, PENNSYLVANIA.

Design No. 4,041, dated May 17, 1870.

DESIGN FOR A WHEEL-HOLDING BLOCK FOR A CASTER.

The Schedule referred to in these Letters Patent and making part of the same.

To all whom it may concern:

Be it known that I, SAMUEL J. PARKER, of Williamsport, county of Lycoming and State of Pennsylvania, have invented and produced a new and original Design for a Wheel-holding Block for a Caster, of which the following is a description.

My wheel-holding block is made of iron and cast in a single piece.

A is a plate, having a hole at *g*, through which a rivet passes to secure it to a large circular plate, shown in red outline.

From the plate A rise standards B B, and from each side of the forward end of the plate A, but outside of B B, project laterally, but in a backward direction,

loops or ears C C, having the openings E E, of equal size at bottom, and top and rounded as shown. The ears C C and the standard B B are to be provided with holes for the axles of suitable wheels.

In figs. 1 and 2 the block is shown in an inverted position, and without the large wheel.

I claim as my invention—

The design for wheel-holding block for casters, as described and shown.

S. J. PARKER.
